INVENTOR

George F. Greene

UNITED STATES PATENT OFFICE.

GEORGE F. GREENE, OF PROVIDENCE, RHODE ISLAND.

DESIGN FOR A SCARF-PIN.

SPECIFICATION forming part of Design No. 23,780, dated November 6, 1894.

Application filed October 6, 1894. Serial No. 525,187. Term of patent 3½ years.

To all whom it may concern:

Be it known that I, GEORGE F. GREENE, a citizen of the United States, residing at Providence, in the county of Providence and State 5 of Rhode Island, have invented and produced a new and original Design for Scarf-Pins, of which the following is a specification, reference being had to the accompanying drawing, forming part thereof.

10 The head or ornamental portion of the scarf-pin has the outline, shape and appearance of a sharp-featured old woman, in side view, sitting in a wicker basket with her knees drawn up and showing above the top of the basket, her right hand supporting her chin. 15 She appears attired with a cloak having a

short cape blowing out from the shoulders, and a steeple-crowned broad brimmed hat is upon her head. A fagot-broom extends from her elbow upward to the rear of and above 20 her head. The whole is placed at a slight angle with the line of the pin tongue, tipping forward in the direction in which said figure is facing.

What I claim is—

25 The design for a scarf-pin herein shown and described.

GEORGE F. GREENE.
